UNITED STATES PATENT OFFICE

THOMAS B. DRAPER, OF OAKLAND, CALIFORNIA

FOLDING BED

Application filed January 29, 1930. Serial No. 424,207.

This invention relates to a folding bed of the type most commonly termed "Chesterfield bed" which may be used either as a chesterfield or as a bed.

5 It is the principal object of the present invention to generally improve the construction and operation of beds of the character referred to.

In practicing the invention, I provide a 10 spring which can be folded to enclose a full size mattress and bedding but which when unfolded presents an unbroken spring area. Head boards are connected with the spring in such a manner that when the spring is unfolded the projected part is fitted with head 15 boards. The construction and mounting of the spring is such that when folded, the seat of the chesterfield will be of normal height and when unfolded the spring will be disposed 20 at ordinary bed height from the floor.

One form which the invention may assume is exemplified in the following description and illustrated by way of example in the accompanying drawings, in which:

25 Fig. 1 is a partial plan view of the device with the spring in folded position.

Fig. 2 is a partial plan view with the spring unfolded.

Fig. 3 is a partial view in front elevation 30 with the front covering removed.

Fig. 4 is a partial front elevation with the spring in unfolded position.

Fig. 5 is an end view of the device with 35 the spring in unfolded position.

Fig. 6 is an end view of the device with one of the end members removed.

Figs. 7 and 8 are end views of the device 40 with one of the end members removed and showing the spring structure being unfolded.

Fig. 9 is a fragmentary view in perspective showing the manner in which the end members are connected with the end frames.

Referring more particularly to the accompanying drawings, 10 indicates a frame fitted 45 with removable end members 11. These end members are upholstered to conform with an upholstered back rest 12 and an upholstered seat 14. When the device is in folded position as illustrated in Figs. 3 and 6 the end

members, back rest and seat 14 unite to form an upholstered chesterfield.

The frame 10 includes end frames 15 having legs 16 which support the structure from the floor. These legs are connected together 55 in each end frame by transverse members 17 and are braced by braces 18. Arranged between the end frames is a spring frame 19 which is collapsible as will be described. At each end of the spring frame is an end rail 60 which is divided into three parts 21, 22 and 23. The three parts of each end rail of the spring frame are in alignment.

When the bed is unfolded as illustrated in Fig. 5, the portions 21 and 23 of the end rails 65 of the spring frame are disposed in the same horizontal plane while the section 22 is slightly elevated. For this reason the adjacent ends of the sections 21 and 23 are fitted with right angular portions 24 to which the 70 ends of the section 22 are pivoted, thus forming a pivotal connection between the three parts. The section 21 of each end rail is pivoted at its inner end to the adjacent end frame 15 as at 25.

When the spring is in unfolded position, the sections 23 of the end rails thereof are adapted to engage lugs 26 on the end frames 15 so as to support the inner portion of the spring. The outer portion of the spring is supported 80 by an open frame 27 which extends at right angles to the section 21 of the end rails of the spring frame. This open frame 27 extends vertical when the bed is in folded position and forms the back frame for the back rest 85 12. When the spring is unfolded, however, the frame 27 depends downwardly to engage the floor and cooperates with the end frames 15 in supporting the spring.

The back rest 12 is pivoted as at 28 to brackets 29 extending at right angles to the end rails 20 of the spring frame and contiguous to the back frame 27. Springs 30 are connected at one end to the open frame 27 as at 31 and at their other ends to the back rest 12 95 at a point eccentric to the pivotal point 28. These springs act to turn the back rest 12 to the position shown in Fig. 5 when the bed is unfolded.

I desire to point out that the bed spring is 100

provided with an upper marginal edge 32 formed of stiff wire rod. This rod is jointed as at 33 and 34 in substantial alignment with the pivotal connections between the sections 5 of the end rails of the spring frame. The spring area is formed of evenly spaced coil springs and is entirely unbroken. This is quite a feature as it makes the spring much more comfortable than springs in prior folding 10 beds which were sectional.

It will be noticed from the drawings that the rows of the coil springs which form a part of this yielding structure are so arranged that the pivotal points of connection between 15 the sections of the spring will permit the spring to fold along lines indicated by A and B in Fig. 2 and thus in effect the spring is in three relatively folding sections as follows: outer section C, intermediate section 20 D and inner section E. The width of the intermediate section D so separates the sections C and E that a full size mattress and bedding may be folded within the spring as illustrated in Fig. 8.

25. To maintain the bedding in proper position when the spring is folded, I provide an apron 35 which extends longitudinally of the spring along the outer edge thereof. This apron is preferably of fabric and is connected 30 at its other end to a bail 36. This bail is of the same length as the spring and the ends of its legs are pivoted to the spring frame as at 37. This bail is disposed so that when the bed is in open position it may lie in an un- 35 obstructing position as illustrated in Fig. 5. When the spring is folded, however, this bail may be moved to the position shown in Fig. 8 and latched as at 39 to the edge of the inner section E so as to connect the sections and 40 maintain them in folded position with the bedding therein. When moving the bail 36 to the position shown in Fig. 8 the apron 35 will form a covering for the open end of the folded bed spring structure and maintain the 45 covers in proper position as illustrated.

Another feature of the present invention is the provision of head boards 40 which are provided to cooperate with the end members 50 11 when the bed is extended. These head boards are connected to the spring frame and are slightly resilient in character. The provision of these head boards makes the bed more comfortable as they provide means for maintaining the pillows and bedding in position 55 on the bed, and also they act to aid in properly holding the bedding and mattress in position when the structure is folded.

In order to make it easy to open and close 60 the bed I provide counterbalancing springs 41 which are connected to links 42 in turn connected to the front lugs 24 at the point of pivotal connection between these lugs and the sections 22 of the end rails of the spring frame. These springs 41 are so disposed that 65 they counterbalance the weight of the folding

structure when it is being opened and when it is being closed. This can be fully comprehended from Fig. 7 where it is seen that as the structure opens, the spring will be under tension. Likewise, as soon as the lugs 24 pass 70 over center, the spring will again be placed under tension so as to yieldingly resist the closing of the structure. Thus, the springs 41 counterbalance the folding structure both when it is being opened and when it is being 75 closed; thus rendering the device easy to handle.

In operation of the device it is constructed and assembled as illustrated in the drawings. The end members 11 may be separately upholstered and connected to the end frames 15 by latch mechanisms 15a shown in Fig. 9. It will be noticed that the seat cushion 14 is secured to the sections 21 of the end rails of 80 the spring frame.

Assuming that the device is in use as a chesterfield as illustrated in Fig. 6 and it is desired to unfold it and use it as a bed it is only necessary to grasp the back rest 12 and swing it forwardly. This will be aided by 85 the springs 41 and the entire folding structure will pivot about the pivot points 25. This is continued until the folding structure reaches the position shown in Fig. 8 at which time the back frame 27 will bear on the floor and the back rest 12 will assume the position shown in Fig. 8. The bail 36 is then disconnected and moved to an unobstructing position or that shown in Fig. 5. The sections D and E are then swung about the pivot points 90 24a to dispose the section D in a horizontal position which swinging movement is continued by swinging the section E about the pivot points 24b to dispose this section in a horizontal position. The mattress may then 95 be spread over the spring and the bed made up for use.

When it is desired to fold the bed, the sections D and E of the spring are folded relative to the section C. The bail 36 is then moved to the position shown in Fig. 8 and connected with the section E moving the apron to position to hold the bedding in place. When the bail is moved to the position 100 shown in Fig. 8 it engages a cam surface on each head board 40 and moves the head boards inwardly to a position where they will clear the end frame 15. The entire structure is then swung to the position shown in Fig. 6. As before stated, the springs 41 so counterbalance the structure that a minimum of effort is required to move it from one position 105 to another.

When the folding structure is swung to the 110 position shown in Fig. 6, the sections 21 of the end rails of the spring frame will engage the lugs 26 on the end frame 15. These lugs 26 also engage the sections 23 when the bed is unfolded to support the same. By reference 115 to Fig. 7 it will be noticed that these lugs 26 120

do not prevent the closing of the structure as it will clear the same by permitting the inner lugs 26 to pass between the sections 22 and 23 when the folded structure is being moved to closed position.

5 While I have shown the preferred form of my invention, it is to be understood that various changes may be made in its construction by those skilled in the art without departing 10 from the spirit of the invention as defined in the appended claims.

Having thus described my invention, what I claim and desire to secure by Letters Patent is:

15 1. A device of the character described including a frame, a folding spring pivotally connected to the frame, said spring including an outer section, an inner section and an intermediate section relatively foldable where- 20 by the inner section may be arranged over the outer section at a distance therefrom equal to the width of the intermediate section, a bail having its legs connected to the outer section, the intermediate portion of the bail being 25 adapted to be detachably connected with the outer side of the inner section to maintain the sections in folded relation so that the spring may pivot about its pivotal connection with the frame, and an apron attached 30 along the outer edge of the outer section and to the intermediate section of the bail to enclose the space between the free edges of the sections when the spring is folded and the bail positioned to connect the same.

35 2. A device of the character described comprising a sectional foldable spring, a bail on one of the spring sections engageable with another of the sections to secure the sections in a folded position, and an apron attached 40 to the bail and one section to form a receptacle for bedding when the spring is folded.

3. A device of the character described comprising a folding frame, a spring carried by the frame and including outer, inner and 45 intermediate sections articulately connected and adapted to be folded to a position in which the inner and outer sections are opposite each other, means releasably securing the sections in a folded position and an apron 50 member carried by said means and extending between edges of the inner and outer sections when folded.

THOMAS B. DRAPER.
